(57) **CLAIM**

The ornamental design for a cooler stand, as shown and described.

DESCRIPTION

FIG. 1 is a front, top and left perspective view of a cooler stand, showing our new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is a front bottom right rear bottom perspective view thereof;

FIG. 9 is a front bottom right perspective view thereof, in use condition; and,

FIG. 10 is a front top left perspective view thereof, in use condition.

The broken lines shown represent environmental structure and form no part of the claimed design.
